(57) **CLAIM**

The ornamental design for sport smartglasses having flat connector hinges, as shown and described.

DESCRIPTION

FIG. 1 is a front top perspective view of sport smartglasses having flat connector hinges showing the temples attached to the front frame showing our new design;

FIG. 2 is a front view thereof;

FIG. 3 is a rear view thereof;

FIG. 4 is a side right view thereof;

FIG. 5 is a side left view thereof;

FIG. 6 is top view thereof;

FIG. 7 is a bottom view thereof;

FIG. 8 is a front top perspective view thereof showing the temples detached from the front frame;

FIG. 9 is a front view of the temples shown separated for ease of understanding;

FIG. 10 is a rear view of the front frame shown separated for ease of understanding;

FIG. 11 is a right side view of the sport smartglasses having flat connector hinges showing the temples detached from the front frame for ease of understanding;

FIG. 12 is a left side view of showing the temples detached from the front frame for ease of understanding thereof;

FIG. 13 is top view showing the temples detached from the front frame for ease of understanding; and,

FIG. 14 is a bottom view showing the temples detached from the front frame for ease of understanding.

The broken lines in the drawings are for the purpose of illustrating unclaimed portions of the sport smartglasses having flat connector hinges and form no part of the claimed design.

1 Claim, 10 Drawing Sheets
